Inventor:

E. W. Woodruff.

United States Patent Office.

EDMUND W. WOODRUFF, OF WASHINGTON, DISTRICT OF COLUMBIA,
ASSIGNOR TO HIMSELF AND B. H. CAMP, OF SAME PLACE.

Letters Patent No. 68,822, dated September 10, 1867.

IMPROVEMENT IN OVER-SOLES FOR BOOTS AND SHOES.

The Schedule referred to in these Letters Patent and making part of the same.

TO ALL WHOM IT MAY CONCERN:

Be it known that I, EDMUND W. WOODRUFF, of the city of Washington, District of Columbia, have invented a new and improved Mode of Attaching Soles to Shoes; and the following is a full and exact description thereof, reference being had to the accompanying drawings, and to the letters of reference marked thereon, in which—

Figure 1 is a view of a shoe with the sole attached.

Figure 2 is a perspective view of the sole, showing in red lines the elastic portion when stretched.

Figure 3 is an edge view of the clasp.

Figure 4 is a top view of the same.

The object of my invention is to provide an over-sole, sandal, or creeper which can be instantly attached or detached without alteration to the shoe or the use of any tool.

My invention consists in attaching to a sole, of rubber, leather, or any other suitable material, an elastic strap and hooked clasp, which, in connection with the toe-piece, holds it securely to the shoe, but in such a manner as that it can be removed at pleasure.

To enable others skilled in the arts to make and use my invention, I will proceed to describe it in detail.

I construct my over-sole A of any suitable material, such as rubber, leather, wood, or metal, to the rear end of which I attach an elastic strap, B, in connection with a clasp, C. The best form of sole is that shown in fig. 2, as the toe-piece D and sides E E prevent dirt or water from getting between the soles, and at the same time, in connection with the elastic B and clasp C, hold it securely to the shoe. The clasp C should be of spring metal, and curved, as shown in fig. 3, the ends c c being bent so as to form hooks.

To attach the sole to a shoe, the shoe should be inserted into it the same as into an ordinary sandal, and then, by taking hold of the clasp and drawing it back to the narrow part of the sole, pressing it in the centre, when the hooks c c will pass over the edges of the sole, and being let go, the contraction of the rubber or elastic strap will draw the clasp forward to a wider part of the sole, thus holding it securely in place. To remove the sole it is only necessary to press the clasp back to the narrow part of the shoe-sole, when it is free to come off.

The advantages of my improved over-sole are many and obvious. It will readily be seen that it is applicable to any and all styles of boots, shoes, or gaiters, being made of different sizes to suit the requirements of the market. The elastic strap and clasp may be attached to any kind of sole, sandal, or creeper. As a matter of economy, it is of the first importance, as it can be manufactured at small cost and worn as a half sole, instead of employing a shoemaker to sew or peg on taps in the ordinary way. For children's wear they may be made with metal toe-pieces, thus providing a durable sole for ordinary wear, which may be taken off when in the house or on extra occasions. As a sandal it will take the place of over-shoes to a great extent, being, when made of rubber, sufficient protection to the feet to prevent dampness, does not sweat the feet, is much lighter, and gives a neat appearance to the shoe. If worn as a creeper, to prevent slipping on snow or ice, & c., with sharp metal points attached to the sole, its advantage is equally apparent, as the ease with which they can be attached and detached render them all that is desired.

Having thus fully described my invention, what I claim, and desire to secure by Letters Patent, is—

Making the rear end of an over-sole of elastic rubber, to which is attached a spring-clasp, operating substantially in the manner and for the purposes specified.
